UNITED STATES PATENT OFFICE.

WILBER EARL ADAMS, OF DETROIT, MICHIGAN.

HOLDING MEANS FOR DENTURES.

Application filed February 14, 1924. Serial No. 692,744.

This invention relates to holding means for dentures, and my invention aims to furnish an artificial denture or plate with a sanitary device for retaining a denture, plate 5 or other member against the roof, palate or tissues of the mouth to avoid any wobbling, shifting, abrasive or irritating action of the denture in the mouth, thus relieving the wear of a denture of any conscious effort of 10 keeping the denture in place. By firmly anchoring the denture on the palate there may be proper mastication of food and a hygienic or sanitary condition can be maintained within the mouth conducive to good health.

15 My invention further aims to furnish a denture with a non-vulcanizing suction member that is firmly anchored in the denture and easy to flex and produce a suction action which will cause the denture to firmly 20 adhere to the palate until forcibly removed. There are various ways of anchoring the suction member in the denture and on account of dentures varying in configuration it is obvious that the suction members may 25 be made of various sizes and shapes. It is in this connection that my invention aims to provide a suction member of maximum size that may be reduced for fitting to any size of denture, thus obviating the necessity of 30 a dentist maintaining a stock of suction member on hand for application to various kinds of dentures.

My invention will be hereinafter specifically described and then claimed and reference will now be had to the drawing, 35 wherein

Figure 1 is a longitudinal sectional view of a denture provided with a suction member;

40 Fig. 2 is a plan of the denture and suction member;

Fig. 3 is a plan of the suction member removed from the denture, and

45 Fig. 4 is a cross sectional view of the same mounted in a denture.

In the drawing, the reference numeral 1 denotes a denture or plate having an opening 2, and 3 denotes a flexible or resilient suction member having marginal edges 4 em- 50 bedded in the wall of the opening 2. This is accomplished when making the denture. The suction member 3 is preferably of metal or a non-vulcanizing material and said suc- 55 tion member is set in the mold in which the

denture is made by vulcanizing rubber or 55 other material, so that when the denture is complete the marginal edges of the suction member are firmly and neatly anchored in the wall of the opening 2.

The suction member 3 has its greater por- 60 tion concavo-convex, particularly within the boundary of a depressed or bead-like rim 5 which contributes towards the flexibility or resiliency of the suction member, to permit of said suction member being pressed 65 by a finger piece in the mouth to reverse the convexity of the suction member, whereby air will be expelled from the opening 2, be- 70 tween the suction member and the roof or palate 6 of the mouth 7. When the suction member assumes normal position, as shown in Fig. 1, a partial vacuum will have been produced between said suction member and the palate 6 and a constant reduction of at- 75 mospheric pressure between the suction mem- 75 ber and the palate will tend to firmly hold the denture 1 against the palate.

There are various ways in which the suc- 80 tion member may be anchored in the walls of the opening 2. For instance, in Figs. 3 and 4, I show the marginal edges 4 of the suction member 3 provided with a series of slots or openings 8 and when the suction member has the denture molded about it the denture material enters the slots or openings 85 8 and positively anchors the suction member within the opening 2, with the rim 5 con- 85 tinuous to the walls of said opening.

What I claim is:—

In a denture having an opening, a flexible 90 non-vulcanizable suction producing member of relatively thin material, said member hav- 95 ing a depressed portion adjacent its edges and openings between said depressed portion and the edges of said member, said member having its edges anchored in and between the upper and lower faces of the denture with the denture material entering the openings of said member, so that the member will be firmly held and permit of an exposed portion 100 of said member wholly within the denture opening being manually flexed upwardly for air excluding purposes and said member stressed to the extent of rebounding when released for producing a denture holding re- 105 duction of atmospheric pressure.

In testimony whereof I affix my signature.

WILBER EARL ADAMS.
